CLAIM

The ornamental design for a pacifier shield, as shown and described.

DESCRIPTION

FIG. 1 is a front elevational view of a pacifier shield showing my new design;

FIG. 2 is a right side elevational view thereof, the left side being a mirror image thereof;

FIG. 3 is a top plan view thereof;

FIG. 4 is a bottom plan view thereof; and

FIG. 5 is a rear elevational view thereof.

The broken line showing of a nipple in FIGS. 2, 3, and 4 and the broken line showing of the bear head design in FIGS. 1, 2, 3, and 4 are for illustrative purposes only and form no part of the claimed design.

FIG. 3

FIG. 2

FIG. 4

FIG. 5
